VALVE MECHANISM.

1,199,070.

Specification of Letters Patent. Patented Sept. 26, 1916.

Application filed May 16, 1913. Serial No. 767,987.

To all whom it may concern:

Be it known that I, Hugo A. HECKER, of Cincinnati, in the county of Hamilton and State of Ohio, have invented certain new and useful Improvements in Valve Mechanisms; and I do hereby declare the following to be a full, clear, and exact description of the same, reference being had to the accompanying drawings, forming a part of this specification, and to the reference-numerals marked thereon.

My invention relates to valve mechanisms of the type embodied in washing machines, and structures of a similar character, where it is desirable at certain intervals to drain the receptacle by holding open the valve, and it has for its object to provide a convenient and simple arrangement by which the valve is normally in close engagement with the valve body to prevent the discharge of the contents of the receptacle, and so that by a very slight operation the valve may be opened, and is thereafter automatically held in open position until the receptacle is empty.

To these and other ends the invention consists in certain improvements and combinations of parts all as will be hereinafter more fully described, the novel features being pointed out in the claims at the end of the specification.

In the drawings: Figure 1 is a vertical sectional view of a preferred embodiment of my invention, the valve being closed; Fig. 2 is a similar view with the valve in open position; Fig. 3 is a vertical sectional view on the line 3^a—3^a of Fig. 1; Fig. 4 is a detail sectional view on the line 4^a—4^a of Fig. 2, and Fig. 5 is a detail elevation of the treadle mechanism.

Similar reference numerals throughout the several figures indicate the same parts.

According to the present embodiment of the invention, 1 designates the valve body which may be attached to the liquid receptacle of the machine in any convenient manner, as usual in this class of apparatus and to this end, said body is preferably provided with openings to receive the bolts 2 which engage the face plate 3, the latter being secured to the receptacle by suitable attaching means through the openings 4.

The valve body is provided with the valve seat 5 which is adapted to receive the valve 6, the latter being arranged for vertical

movement in the valve body, and weighted sufficiently so that it is normally held in its closed position, as shown in Fig. 1, by gravity. In order to properly center the valve, and to guide it in its up and down movements, it is provided with radial wings 7 and a flange 8 which coöperate with the inner surface of the valve body, the latter having a downwardly extended collar 9 to form a bearing surface of sufficient extent to guide the valve properly. Any suitable means may be employed to limit the upward movement of the valve, and this is preferably accomplished by a pin or projection 10 carried by one of the ribs 7 and arranged for engagement with the bottom of the flange 9.

In order to effect operation of the valve to open it, I provide the lever 11, pivoted to the valve body at 12 and having pivotal connection with the valve at 13 by means of the lugs 14. The lever 11 is adapted to be operated by the foot engaging portion 15 and when the latter is depressed, the valve is raised as shown in Fig. 2 to empty the receptacle of its contents, the weight of the valve being sufficient under normal conditions to overcome the weight of the outer end of the lever 11 to force itself into tight engagement with the valve seat.

It is desirable that some means be provided which will automatically come into operation when the valve is raised, so as to hold it open as long as necessary, and to this end, I preferably provide the operating lever with locking means arranged to coöperate with the valve body when the lever is depressed, to lock the valve against closing, and in the present embodiment, this means consists of a locking member or pawl 16 pivoted on the lever and adapted to coöperate with a locking shoulder 17 on the valve body. The locking member 16 is arranged to be automatically moved into engagement with the locking shoulder 17 when the lever 11 is depressed, and is, therefore, preferably spring actuated. 18 is a connecting rod pivoted to the pawl 16 and guided in the post 19, the locking member being moved into locking position by means of a spring 20 surrounding said connecting rod and arranged between the post 19 and an adjustable stop 21. The connecting rod 18 is pivoted to one arm of a bell crank 22 which is pivoted at 23 to the lever 11 and

carries a treadle or foot engaging portion 24 arranged adjacent to the previously mentioned foot engaging portion 15 on the lever 11, as shown more clearly in Fig. 5. Steam 5 is supplied to the apparatus from any suitable source through a hollow connection 25 which is threaded into the valve body and leads to a passage 26 having communication with the interior of the chamber through a 10 series of openings 27. By this arrangement, the steam coming in strikes the wall 28 and is thereby spread out into more or less of a thin sheet which passes through the openings 27 and effects a proper intermingling 15 with the water in the receptacle.

In the operation of the device, when it is desired to discharge the contents of the liquid chamber, the valve 6 is raised by depressing the lever 11, whereupon the locking member 16 is moved into engagement with the valve body as shown in Fig. 2, and holds the valve in its elevated position until the receptacle is drained. The valve is returned to its closed position by depressing the foot 25 engaging portion 24, which withdraws the locking member from the shoulder 17, and permits the valve to close under its own weight.

I claim as my invention:

30 1. A valve mechanism for washing machines comprising in combination a valve body having a seat and a gravity controlled valve coöperating therewith, a lever pivotally mounted on the valve body having pivotal connection with the valve and operating when moved downwardly to open the valve, a shoulder formed on the valve body, a lock-

ing member pivotally mounted on the lever and automatically coöperating with said shoulder to hold the valve open when the 40 lever is moved downwardly, an operating device pivoted upon the lever and operating when moved downwardly to release the locking member and permit the valve to close, and a connection between the operating device and the locking member.

2. A valve mechanism for washing machines comprising in combination a valve body having a seat and a gravity controlled valve coöperating therewith, a lever pivotally mounted on the valve body having positive connection with the valve and operating when moved downwardly to open the valve, a shoulder formed on the valve body, a locking member pivotally mounted on the 50 lever and acting automatically to engage said shoulder and hold the valve open when the lever is moved downwardly, an operating device pivoted on the lever and operating when moved downwardly to release the 55 locking member and permit the valve to close, a connection between the operating device and the locking member, and foot engaging portions carried by the operating device and said lever respectively and arranged in juxtaposition at one side of each other and both being operable in a downward direction for opening or closing the valve.
